UNITED STATES PATENT OFFICE.

EDWARD J. McDADE, OF ROCHESTER, NEW YORK, ASSIGNOR TO PRITCHARD-STAMPING COMPANY, OF ROCHESTER, NEW YORK, A CORPORATION OF NEW YORK.

COUPLING DEVICE.

1,105,034.

Specification of Letters Patent.

Patented July 28, 1914.

Application filed April 8, 1914. Serial No. 830,432.

To all whom it may concern:

Be it known that I, EDWARD J. McDADE, a citizen of the United States, and resident of Rochester, in the county of Monroe and 5 State of New York, have invented certain new and useful Improvements in Coupling Devices, of which the following is a specification.

This invention relates to a device adapted 10 particularly for coupling or locking together the oil-font and the body-hoop of a lantern, although it is also applicable, in its main features, to various other articles in which annular or cylindrical members are 15 to be coupled together.

The main object of the invention is to produce a coupling-device, of simple and inexpensive form, which will permit the parts connected thereby to be readily engaged 20 with, and disengaged from each other, but which will lock them securely in such engagement.

As applied specifically to lanterns, the invention has the further object of providing for the admission, to the body-hoop, of the wick-raiser of the burner, while closing, against the entrance of air, the slot 25 through which the shaft is introduced.

To the foregoing ends I employ a construction in which the oil-font is locked to 30 the body-hoop by means of a resilient ring, and in which this ring is held securely in operative position by the cam-like action of a rotatable annular member surrounding 35 the body-hoop. I further employ the rotatable member as means for both closing the slot through which the wick-raiser shaft is introduced into the body-hoop, and contributing to the locking action of the device 40 by its engagement with this shaft.

In the accompanying drawings:—Figure 1 is a side-elevation, partly in vertical section, of the lower part of a lantern embodying the present invention; and Figs. 2 and 45 3 are horizontal sections, on the line 3—3 in Fig. 1, looking upwardly, showing the parts respectively in unlocked and locked position.

The invention is illustrated as embodied 50 in a lantern of a well-known type, in which the body of the lantern is provided with a downwardly-projecting, cylindrical, sheet-metal hoop 5, while the oil-font 6 is provided with an upwardly-projecting cylindrical portion adapted to be received with-

in the hoop. The hoop and the oil-font are coupled together through the interposition of a divided ring 7 formed of resilient wire. This ring has outwardly-bent portions forming projections 8, which extend 60 through perforations in the body-hoop 5, as shown in Figs. 2 and 3, the ring being thus retained within the hoop. To coöperate with this ring the oil-font is provided with an annular channel 9. The normal 65 form of the ring, as shown in Fig. 2, is such that it tends to spring inwardly to a diameter less than that of the oil-font, so that when the oil-font is introduced to the body-hoop the ring springs over its end and 70 then snaps into the channel 9. This arrangement, in itself, is sufficient to cause the retention of the oil-font, but to provide a more secure and positive locking action, I employ means for locking the ring in 75 position in the channel. To this end the body-hoop is surrounded by a rotatable annular sheet-metal member 11. This member is provided with openings 12 which, in one position of the rotatable member, coincide with the projections 8 on the locking-ring so that the ring is free to expand when 80 the oil-font is introduced or removed. After the oil-font has been introduced, however, the rotatable member is turned from its 85 normal position, and this causes it to have a cam-like action upon the projections 8, forcing them inwardly from the position of Fig. 2 to the position of Fig. 3, and thereby locking the ring against the expansion necessary to permit the removal of the oil-font. In this position of the parts the rotatable member is, in turn, retained securely in position by its frictional engagement 90 with the projections 8. 95

The oil-font is shown as provided with the usual burner 16, having a wick-raiser of the ratchet type provided with the usual hand-wheel mounted on a shaft 13. A slot 15 in the body-hoop provides for the introduction of this shaft, and the rotatable member 11 is provided with a slot 14 having a vertical portion for the same purpose, this portion of the slot 14 coinciding with the slot 15 when the parts are in the unlocked position of Fig. 2. The upper part of the slot 14 extends horizontally, and when the member 11 is turned to locking position this horizontal portion is engaged with the shaft 13, while the vertical por- 105 110

tion is moved out of registry with the slot 15. By this arrangement the slot 15 is closed against the admission of air, and at the same time the oil-font is more securely locked in place by the coöperation of the shaft 13 and the member 11 in the manner of a bayonet-joint.

My invention is not limited to the embodiment thereof hereinbefore described and illustrated in the accompanying drawings, but may be embodied in various other forms within the nature of the invention as it is defined in the following claim.

I claim:—

15 In a coupling-device, the combination, with an inner member, an outer annular member, in which the inner member is to

be locked, provided with spaced openings, and a spring-ring interposed between said members and provided with projections extending outwardly through said openings, of a rotatable annular member mounted on said outer annular member, said rotatable member having portions coöoperating, in the manner of a cam, with said projections on the spring-ring, whereby the ring, through partial rotation of the rotatable member, may be forced inwardly and held in locking engagement with said inner member.

EDWARD J. McDADE.
